UNITED STATES PATENT OFFICE.

FREDRICH J. RODE, OF CHICAGO, ILLINOIS, ASSIGNOR TO MARQUETTE TOOL & MFG. COMPANY, OF CHICAGO, ILLINOIS, A CORPORATION OF ILLINOIS.

CUSHION FOR SHEET-METAL PRESSES.

Application filed May 5, 1927. Serial No. 188,969.

This invention relates to improvements in cushions particularly adapted, though not necessarily limited in its use for sheet metal presses in which the metal is shaped by means of co-operating dies, one of which dies is reciprocable toward and away from the other, the work being clamped or held by means of a blank or work holding element that co-operates with a reciprocable die member, the blank or work holding member being resisted in its movement in one direction by the said cushion, and one of the objects of the invention is to provide an improved combined hydraulic and pneumatic cushion of this character whereby a double drawing operation upon the material may be produced in what is commonly known as a single acting press, that is in a press in which the double drawing operation is performed upon a single stroke of the ram of the press and at different points in the cycle of movement of the ram in one direction.

A further object is to provide an improved cushion of this character embodying hydraulic and pneumatic cushion elements, one of which is rendered inactive while the other is active, and improved means whereby the stress exerted against the work by the cushion elements may be transferred from one of said cushion elements to the other, automatically and at a predetermined time in the cycle of operation of the press.

A further object is to provide improved means whereby the resistance pressure of the said cushion may be varied at will.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention, and in which—

Figure 1 is a view in elevation of a sheet metal press having a cushion embodying the principles of this invention attached thereto, parts being shown in section, parts broken away, and parts omitted.

Figure 2 is an enlarged detail sectional view of a portion of the cushion and the co-operating dies, with the parts in one position or in the position they will assume at the completion of the first step in the drawing operation.

Figure 3 is a view similar to Figure 2, showing the parts in the position they will assume at the end of the second step in the operation or upon the completion of the draw.

Referring more particularly to the drawings the numeral 10 designates generally a sheet metal press having a bed or bolster plate 11, uprights 12, a reciprocating ram 13, a crank shaft 14, and a link 15 connecting the ram with the crank shaft and which crank shaft is driven in any suitable manner and from any suitable source of power, not shown, preferably by means of a gear wheel 16 meshing with an internal gear wheel 17.

All of the above referred to parts are of the ordinary and well known construction.

Mounted upon the bed plate 11 in any suitable manner is a die 18, having a co-operating movable die member 19. Encompassing the die member 19 and supported by the bed plate 11 is another die 20, having a movable die member 21.

Beneath the bed of the press and preferably arranged within a pit 22 is a support 23 held in position in any suitable manner from a fixed part of the machine, preferably by means of hanger rods 24. Supported by the member 23 is a cylinder 25 of any desired size and diameter, in which cylinder a piston 26 is reciprocable. Connected with the piston 26 is a piston rod 27 which passes through a suitable stuffing box 28 in the end of the cylinder. The piston rod 27 is connected with a pressure or pin plate 29 preferably by means of a suitable fastening device 30, and resting upon the pad or plate 29 or pins 31, any number of which may be provided and these pins support the movable member 19 which co-operates with the die 18, the pins 31 passing loosely through the bed plate 11 and are of a length to normally hold the top of the member 19 substantially flush with the top of the die 18 when the pad or plate 29 is at the limit of its upward movement.

The end 32 of the cylinder 25 is shaped to form a piston, preferably of a cup shaped configuration and telescoping over the piston 32 is a cylinder 33, the bottom of which is open. The cylinder and piston 32 are held against displacement with respect to each other in any suitable manner such as by means of a fastening ring 34 secured to the cylinder 33, which engages under a circumferential flange 35 on the piston 32.

The piston rod 27 passes loosely through the end of the cylinder 33 and a stuffing box or packing 36 may be provided to form a fluid tight joint.

5 Supported by the cylinder 33 are pins 37, any number of which may be provided and these pins pass loosely through the bed or bolster plate 11 and are of a length to support the movable members 21 of the die 20.

10 A fluid, such as air, is supplied to the cylinder 33 under any desired predetermined pressure and from any suitable source, preferably from a tank or container 38, through the medium of a pipe 39 which preferably 15 passes through the piston 32.

Within the cylinder 25 is a liquid 40 which may be initially supplied thereto from any suitable source preferably through a pipe 41, having a check valve 42 therein.

20 A predetermined quantity of liquid is supplied to the cylinder 25 and is adapted to be forced from beneath the piston 26 to the upper side thereof, when the piston 26 is lowered, through a pipe or conduit 43 which 25 has communication with the cylinder adjacent the bottom thereof through an opening 44 and also with the top of the cylinder above the piston through an opening 45.

30 A valve 46 is provided for controlling the opening 44. A spring 47 controls the valve 46 and an operating handle 48 serves the means whereby the stress of the spring 47 35 may be varied at will.

In operation the valve 46 is seated with 35 a predetermined pressure of the spring 47 and against which pressure it is necessary to unseat the valve 46 by the pressure upon the liquid 40 exerted by the piston 26 as the latter descends. By the adjustment of the spring 40 47 a variable and predetermined resistance pressure may be imparted to the valve 46.

45 When the valve 46 is unseated the liquid will flow through the conduit 43 to the top side of the piston.

50 When the piston 26 rises the liquid on the top of the piston will be discharged through an opening 49 from the cylinder into a conduit 50 and back into the cylinder through an opening 51 on the other side of the piston.

55 A check valve 52 is provided in the conduit 50 to prevent the liquid from being forced through the conduit 50 when the piston 26 descends. The valve 52 will, however, open under the pressure of the liquid when the piston 26 rises.

It will therefore be manifest that by adjusting the spring 47 any predetermined resistance pressure of the liquid 40 may be exerted upon the movable member 19 which 60 co-operates with the surface 53 of the die 54 that is connected with the ram 13.

Within the conduit 43 a valve designated generally by the reference numeral 55 is provided. This valve may be of any ordinary 65 and well known construction adapted when in

one position, to open the conduit to the passage of liquid and when in another position to close the conduit against the passage of liquid.

This valve 55 is controlled in its operation 70 from any movable part of the cushion or press. In the present form of the invention, however, it is controlled by the movement of the cylinder 33 and is operated first to open and then close the same at predetermined 75 times in the cycle of operation or movement of the cylinder 33. Such operation is accomplished preferably by means of a link 56 which is connected at one end with an arm 57 connected with the valve. The link 56 80 passes through a guide 58 on the cylinder 33 and adjustable collars or nuts 59—60 are provided on the link and so positioned that at a predetermined time in the cycle of lowering movement of the cylinder 33 the guide 58 85 will engage the nut or collar 59 to lower the link and rock the arm 57 to open the valve 55. When the cylinder 33 rises the guide 58 will at a predetermined point during its rising movement engage the nut or collar 60 to 90 again close the valve 55.

This valve 55 and the operation thereof is necessary so as to prevent the lowering of the piston 26 during the first step in the drawing operation as it is necessary to maintain 95 the piston and the pin plate or pad 29 against a lowering movement while the work 61 is being formed over the die 18 and the co-operating member 19, as shown in Figure 2 of the drawings.

100 After the completion of this first step in the forming operation the guide 58 on the cylinder 33 will engage the nut or collar 59 on the link 56 to open the valve 55. A further lowering movement of the ram 13 and die 105 54 from the position shown in Figure 2, will then depress the piston 26. When a pressure is created by the lowering of the piston 26 upon the liquid 40 sufficient to unseat the valve 46 against the stress of 110 the spring 47, the liquid will flow through the conduit 43 to permit the piston 26 and member 19, which co-operates with the die 18, to be lowered to the position shown in Figure 3, whereby the second step in the 115 forming or drawing operation upon the work 61 will be completed.

120 The ram 13 will then ascend and when the pressure of the ram and work upon the cylinder 33 is relieved the fluid (such as air) will enter the cylinder 33 above the piston 32 to raise the cylinder and thereby restore the piston 26 to its normal or elevated position in the cylinder 25 and also the movable members 19 and 21 of the forming dies.

125 This is accomplished by reason of the fact that the pad or pin plate 29 which is connected with the piston rod 27 of the piston 26, is engaged by the cylinder 33 to raise the latter and as the pad or pin plate 29 is raised 130

the piston 26 will be drawn upwardly in the cylinder 25.

As the die member 19 rises it will act as a stripper for stripping the article from the die 18.

A knock out device 63 may be provided in the die 54, if desired.

With this invention it will be manifest that the first drawing operation will be made 10 against the fluid or air pressure element of the cushion while the hydraulic element will maintain the second die against operation until the completion of the first step in the drawing operation. At this time the resistance pressure will then be shifted automatically 15 by means of the control valve 55 from the pneumatic to the hydraulic cushioning elements.

As the cylinder 33 is lowered the fluid will 20 be forced from the cylinder out of the pipe 39 back into the tank or receiver 38.

An automatic regulator or pressure control valve 62, of the ordinary and well known type may be provided in the fluid pressure 25 supply line.

While the preferred form of the invention has been herein shown and described, it is to be understood that various changes may be made in the details of construction and in the 30 combination and arrangement of the several parts, within the scope of the claims, without departing from the spirit of this invention.

What is claimed as new is:—

1. In a sheet metal press a plurality of pressure pads, a pneumatic pressure cushion element for resisting the movement of one of said pads in one direction, a cushion element having a resistance creating liquid therein different from the said pneumatic cushion 35 for resisting the movement of the other pad in one direction, and means for shifting the active resistance pressure from one of said cushion elements to the other at a predetermined point in the cycle of operation of the press.
2. In a sheet metal press a plurality of pressure pads, a pneumatic pressure cushion element for resisting the movement of one of said pads in one direction, a cushion element having a resistance creating liquid therein different from the said pneumatic cushion for resisting the movement of the other pad in one direction, means for maintaining one of said cushion elements inactive during one 50 portion of operation of the press and while the other cushion element is active, and means for rendering the inactive cushion element active.
3. In a sheet metal press, a ram, a plurality of pressure pads, a fluid pressure cushion element for resisting the movement of one of said pads in one direction, an hydraulic cushion element for resisting the movement of the other pad in one direction, means for varying at will the resistance pressure of the 55 hydraulic cushion element, means for maintaining the hydraulic cushion element inactive under the stress of the ram, whereby the said fluid pressure cushion will be active in advance of the hydraulic cushion element, 60 and means for rendering the last recited means inactive at a predetermined time in the cycle of operation of the press to render the hydraulic cushion element active.
4. In a sheet metal press, a ram, a plurality of pressure pads, a pneumatic pressure cushion element for resisting the movement of one of said pads in one direction, a cushion element having a resistance creating fluid therein different from the said pneumatic cushion for resisting the movement of the other pad in one direction, means for varying at will the resistance pressure of the hydraulic cushion element, and means for maintaining the hydraulic cushion element inactive under the stress of the ram, the last recited means being responsive in its operation to a movable part of the press for rendering the hydraulic cushion element active.
5. In a sheet metal press, a ram, a plurality of pressure pads, a fluid pressure cushion element for resisting the movement of one of said pads in one direction, an hydraulic cushion element for resisting the movement of the other pad in one direction, means for varying at will the resistance pressure of the hydraulic cushion element, means for maintaining the hydraulic cushion element inactive under the stress of the ram, and means responsive in its operation to the actuation 90 of the fluid pressure cushion for actuating the last recited means to render the hydraulic cushion active.
6. In a sheet metal press, a ram, a plurality of pressure pads, a pneumatic pressure cushion element for resisting the movement of one of the pads in one direction, a cushion having a resistance creating fluid therein different from the said pneumatic cushion for resisting the movement of the other pad in one direction, one of said cushions being inactive to maintain its respective pressure pad against movement under the stress of the ram of the press while the other pad is movable under the stress of the ram and against the stress 100 of its respective cushion, and means automatically rendering the said inactive cushion active at a predetermined time in the cycle of operation of the press whereby the active stress of the ram upon the work will be transferred from the first to the second recited cushion.
7. In a sheet metal press, a ram, a plurality of pressure pads, a pneumatic pressure cushion element for resisting the movement of one of the pads in one direction, a cushion having a resistance creating fluid therein different from the said pneumatic cushion for resisting the movement of the other pad in one direction, one of said cushions being inactive to maintain

tain its respective pressure pad against movement under the stress of the ram of the press while the other pad is movable under the stress of the ram and against the stress of its 5 respective cushion, means automatically rendering the said inactive cushion active at a predetermined time in the cycle of operation of the press whereby the active stress of the ram upon the work will be transferred from 10 the first to the said second recited cushion, and means for varying at will the resistance pressure of the hydraulic cushion.

8. In a sheet metal press, a ram, a plurality of pressure pads, a pneumatic pressure cushion for resisting the movement of one of the pads in one direction, a cushion having a resistance creating fluid therein different from the said pneumatic cushion for resisting the movement of the other pad in one direction, 15 the last said cushion being inactive to maintain its respective co-operating pad against movement under the stress of the ram of the press while the other pad is movable under the stress of the ram and against the stress 20 of its respective cushion, and means responsive to the actuation of a movable part of the said first said pressure cushion to transfer the working stress of the ram from the first said to the second said cushion.

30 9. In a sheet metal press, a ram, a plurality of pressure pads, a fluid pressure cushion for resisting the movement of one of the pads in one direction, an hydraulic cushion for resisting the movement of the other pad in one 35 direction, said hydraulic cushion being inactive to maintain its respective co-operating pad against movement under the stress of the ram of the press while the other pad is movable under the stress of the ram and against 40 the stress of its respective cushion, means responsive to the actuation of a movable part of the said fluid pressure cushion to transfer the working stress of the ram from the fluid to the hydraulic cushion, and means for vary-

ing at will the resistance pressure of the hy- 45 draulic cushion.

10. A cushioning device for sheet metal presses, said cushion embodying a cylinder and piston members, a liquid in said cylinder for creating a resistance pressure against the 50 relative movement of the piston and cylinder, one end of said cylinder constituting a piston, a second cylinder in which the last said piston operates, means for supplying to the second recited cylinder a fluid different from 55 the said liquid for resisting the relative movement of the last said cylinder and its piston, pressure pads individual to and operating against the stress of the respective cushions, a ram, and means for locking the hydraulic 60 cushion against operation, the last said means being automatically rendered inactive at a predetermined point in the cycle of operation of the press to transfer the operative action of the ram from one to the other of the cushion- 65 ions.

11. A cushioning device for sheet metal presses, said cushion embodying a cylinder and piston members, a liquid in said cylinder for creating a resistance pressure against the 70 relative movement of the piston and cylinder, one end of said cylinder constituting a piston, a second cylinder in which the last said piston operates, means for supplying to the second recited cylinder a fluid different from 75 the said liquid for resisting the relative movement of the last said cylinder and its piston, pressure pads individual to and operating against the stress of the respective cushions, means for locking the hydraulic cushion 80 against operation, and means responsive in its operation to the operation of one of said pads for controlling the said locking means.

In testimony whereof I have signed my name to this specification, on this 26th day 85 of April, A. D. 1927.

FREDRICH J. RODE.
